[57] CLAIM

The ornamental design for a chest protector without epaulette, as shown and described.

DESCRIPTION

FIG. 1 is a front elevational view of a chest protector with epaulette showing our new design;

FIG. 2 is a rear elevational view thereof, the straps broken away for convenience of illustration; and

FIG. 3 is a front perspective view thereof; the straps removed for convenience of illustration.

Fig. 1

Fig. 3
